UNITED STATES PATENT OFFICE.

AUGUSTUS TRAVER, OF NEW YORK, N. Y.

COMBINED GLOVE STRETCHER AND MEASURE.

SPECIFICATION forming part of Letters Patent No. 309,666, dated December 23, 1884.

Application filed January 7, 1884. (No model.)

To all whom it may concern:

Be it known that I, AUGUSTUS TRAVER, of the city, county, and State of New York, have invented a new and Improved Combined 5 Glove Stretcher and Measure; of which the following is a full, clear, and exact description.

The object of my invention is to provide a new and improved glove stretcher and measure for measuring the width of the hand across 10 the knuckles.

The invention consists in a glove-stretcher on which a glove measure or scale is fixed.

The invention also consists in the combination, with a glove-stretcher on which a measure is formed, of a fixed clip and sliding clip, 15 between which clips the hand is placed for measuring it.

Reference is to be had to the accompanying drawings, forming part of this specification, 20 in which similar letters of reference indicate corresponding parts in all the figures.

Figure 1 is a perspective view of my improved combined glove stretcher and measure. Fig. 2 is a cross-sectional elevation of one of 25 the levers forming the same. Fig. 3 is a longitudinal sectional elevation of the sliding clip of the measure.

The glove-stretcher is made in the usual manner of two levers, A and A', pivoted or 30 hinged to each other.

On the outer surface of one of the levers—A, for instance—a measure, B, is fastened, at one end of which a clip or stud, C, is secured on the lever A in such a manner as to 35 project from the same. Grooves a are formed in the sides of the lever A, and the ends of a plate or clip, D, held to slide over the measure B, and bent into the grooves a. The bent ends of the plate D hold the said plate on the 40 lever A, at the same time permitting the plate or clip to slide on the lever. The plate or clip D is provided with an upwardly-projecting plate like the clip C. A spring-strip, E, is secured to the under side of the clip D, to hold 45 it in any desired position on the lever A. The scale or measure B, secured on the outer surface of the lever A, is subdivided, so that it shows the various numbers of gloves for corresponding widths of hands.

50 The usual glove-measures have been made of flexible material only, and were adapted to be passed around the hand at the knuckles,

My improved measure is formed on a rigid object. One side of the hand at the knuckles is placed against the clip C, and the other clip, 55 D, is pressed firmly against the other side of the hand. The number at the inner side of the clip D shows the glove-number for the hand.

I am aware that a glove-stretcher has been heretofore provided with flexible loop or meas- 60 ure arranged in the handle of the stretcher so as to be drawn out for use and returned in the handle by a spring, the said loop or meas- ure being attached to a guide having an in- 65 dex working in a slot of the handle, the outer surface of which is provided with a scale; and I am also aware that a shoemaker's measure, consisting of a graduated bar provided with a stationary block and sliding block, the latter being held on the bar by having its sides bent 70 inwardly into grooves formed in the sides of the said bar, is old, and I therefore do not claim such invention.

Having thus described my invention, what I claim as new, and desire to secure by Let- 75 ters Patent, is—

1. As an improved article of manufacture, a combined glove stretcher and measure con- 80 sisting of two hinged levers, one of which is provided on its outer surface with a measurer, B, a stationary clip, C, and a sliding clip, D, as set forth.

2. In a combined glove stretcher and meas- 85 ure, the combination, with the lever A, pro- vided with the measurer B and the longitudi- nal side grooves, a, of the stationary clip C, and the sliding clip D, having the sides bent into the grooves of the lever, substantially as herein shown and described.

3. In a combined glove stretcher and meas- 90 ure, the combination, with the lever A, pro- vided with the measurer B and the longitudi- nal grooves a, and the stationary clip C, of the sliding clip D, having its sides bent into the 95 grooves of the lever, and the spring E, secured to the under side of the clip, substantially as herein shown and described.

AUGUSTUS TRAVER.
